UNITED STATES PATENT OFFICE.

CHRISTIAN KRAMER, OF NEW YORK, N. Y., ASSIGNOR OF ONE-HALF TO
CHARLES WIRTZ, OF SAME PLACE.

ALARM ATTACHMENT FOR POWER-LOOMS.

SPECIFICATION forming part of Letters Patent No. 622,498, dated April 4, 1899.

Application filed August 31, 1898. Serial No. 689,938. (No model.)

To all whom it may concern:

Be it known that I, CHRISTIAN KRAMER, a citizen of Germany, residing at New York, borough of Bronx, State of New York, have invented certain new and useful Improvements in Alarm Attachments for Power-Looms, of which the following is a specification.

This invention is intended to supply an alarm attachment for power-looms, so that whenever one of the shafts of the same drops an immediate alarm is given, so that the attendant can stop the loom and look for the cause of the interruption and repair the defect before any imperfect goods have been made, which would naturally be the case if the loom continues, and thereby save labor and material.

The invention consists of an alarm attachment for power-looms which is actuated in case any one of the shafts is dropped, said attachment consisting of one or more spring-wire frames located transversely below said shafts and composed of a stationary guide portion having eyes and a yielding spring portion that is depressed so as to close an electric circuit whenever one of the shafts drops for one reason or another, so as to ring an alarm and call thereby the attention of the attendant to the defect, so as to stop the loom.

The invention consists, secondly, of the special construction of the alarm attachment, which will be fully described hereinafter, and finally pointed out in the claims.

In the accompanying drawings, Figure 1 represents a front elevation of a ribbon-loom with my improved alarm attachment shown in position thereon, and Fig. 2 is a perspective view of one of the attachments and the electric conducting-wires arranged in connection therewith.

Similar letters of reference indicate corresponding parts.

Referring to the drawings, A represents the supporting-frame, and B the shafts, of a ribbon-loom of any approved construction. On the longitudinal beams *a* of the frame A are arranged below the shafts B one or more wire alarm attachments C, which are formed of two upright wires *d*, having horizontal guide-eyes *d'* and a V-shaped wire *d''*, that is attached at one end to the longitudinal beams of the sup-

porting-frame A. The free ends of the V-shaped wires *d''* are connected transversely below said eyes *d'* by a wire *d'''* and in addition thereto by a transverse stiffening-wire *d''''* at 55 the apex of the V-shaped wires, as shown in Fig. 2. The V-shaped wire frame has a certain spring action, so that if one of the shafts should become disconnected and drop down on the transverse wire of the attachment the latter 60 will move in the guide-eyes in downward direction, bending on the fastening ends until the lower transverse portion comes in contact with the electric conducting-wires *e e*, that run along the face of the longitudinal 65 beams *a* and form connection with the poles of a battery E, so that an electric alarm D is actuated by the same. The battery may be located at any suitable position near the loom, so as to be called into action as soon as the 70 circuit is closed by the lower end of the transverse lower portion of the wire frame, as shown in dotted lines in Fig. 2.

The alarm attachment enables the attendant of the power-loom to immediately repair 75 any broken cord or other defect connected with the operation of the shafts without waste of time and material heretofore connected with such accidents. The bell is rung as soon as any one of the shafts falls down, for the 80 reason that the alarm attachment is lowered and placed in contact with the electric conducting-wires of the circuit, so that the alarm is rung and the attention of the attendant drawn to the fact that the shafts of the loom 85 are not in good working order. He then knows that he has to immediately stop the loom and repair the defect before further damage occurs. He is thereby enabled to save considerable in time and material, as the imperfect part of the goods, which would naturally have been made if the loom had continued running with one or more shafts out of place, would have to be undone again, the material being wasted and time lost by this operation. 90

Having thus described my invention, I claim as new and desire to secure by Letters Patent—

1. The combination, with the frame of a power-loom, and the shafts of the same, of a 100 wire alarm attachment extending transversely across the frame of the loom below said shafts,

and an electric circuit closed by said alarm attachment when one of the shafts drops on the same, substantially as set forth.

2. An alarm attachment for power-loom, 5 consisting of a V-shaped wire frame located below the shafts and attached at one end to the supporting-frame of the loom and provided with a transverse connecting-wire at the ends of its V-shaped rods, guide-eyes for 10 the free ends of said V-shaped rods, and an

electric circuit closed by the dropping of a shaft upon said wire frame, substantially as set forth.

In testimony that I claim the foregoing as my invention I have signed my name in presence of two subscribing witnesses.

CIRISTIAN KRAMER.
